CLAIM

The ornamental design for a keypad for an anti-theft alarm for automobiles, as shown and described.

DESCRIPTION

FIG. 1 is a front elevational view of the keypad for an anti-theft alarm for automobiles showing my new design, with the cord broken away to indicate indeterminate length;

FIG. 2 is a rear elevational view thereof;

FIG. 3 is a left side elevational view thereof;

FIG. 4 is a right side elevational view thereof;

FIG. 5 is a top plan view thereof; and,

FIG. 6 is a bottom plan view thereof.

FIG. 1

FIG. 2

*FIG. 3**FIG. 4**FIG. 5*

FIG. 6
